DESIGN FOR A GUN SIGHT

Robert M. Lynn, Pasadena, Calif.

Application November 3, 1943, Serial No. 111,578

Term of patent 14 years

(Cl. D30—1)

To all whom it may concern:

Be it known that I, Robert M. Lynn, residing in Pasadena, in the county of Los Angeles and State of California, have invented a new, original, and ornamental Design for a Gun Sight, of which the following is a specification, reference being had to the accompanying drawing, forming part thereof.

Fig. 1 is a top plan view of a gun sight showing my new design.

Fig. 2 is a side elevational view, and
Fig. 3 is a front elevational view of the gun
sight.

I claim:

The ornamental design for a gun sight, as
shown.

ROBERT M. LYNN.
